COMBINATION FLOOR POLISHING AND SCRUBBING MACHINE OR SIMILAR ARTICLE

Henry Dreyfuss, South Pasadena, Calif., assignor to The Singer Company, New York, N.Y., a corporation of New Jersey

Filed Apr. 29, 1964, Ser. No. 79,739

Term of patent 14 years

(Cl. D9—2)

Fig.1

Fig.3

FIG. 1 is a front elevational view of a combination floor polishing and scrubbing machine showing my new design.

FIG. 2 is a rear elevational view of the combination floor polishing and scrubbing machine shown in FIG. 1, and

FIG. 3 is a perspective view of the combination floor polishing and scrubbing machine shown in FIGS. 1 and 2.

I claim:

The ornamental design for a combination floor polishing and scrubbing machine or similar article substantially as shown and described.
